UNITED STATES PATENT OFFICE.

HOWELL W. SOUDER, OF TAMAQUA, PENNSYLVANIA, ASSIGNOR OF ONE-HALF TO W. D. ZEHNER, OF LANSFORD, PENNSYLVANIA.

SIGNAL APPARATUS.

SPECIFICATION forming part of Letters Patent No. 735,418, dated August 4, 1903.

Application filed September 25, 1902, Serial No. 124,796. (No model.)

To all whom it may concern:

Be it known that I, HOWELL W. SOUDER, a citizen of the United States of America, and a resident of Tamaqua, Schuylkill county, State of Pennsylvania, have invented certain new and useful Improvements in Signal Apparatus, of which the following is a specification.

My invention relates in general to signals, and more specifically consists of an improved form of electric lantern by means of which visual signals can be made both in night-time and in day-time.

While capable of various uses, my invention finds its most important application to signal systems for railways, and the form of apparatus illustrated in the drawings is especially designed for use on electric railroads.

It has heretofore been customary to employ electric lamps for signaling purposes on electric roads, but where it is desired to produce colored lights, such as red and green, the signals fail in the day-time—that is to say, when the sun is shining on a lamp having the ordinary colored lens of considerable thickness the external light so far overpowers the relatively feeble internal light given off by the lamp that little or no difference in external appearance is presented whether the lamp is lighted or extinguished. Thus it is impossible to tell in the daylight whether the signal is alive or dead and no information as to the condition of the road is afforded by it. My invention overcomes these difficulties and produces a lamp-signal, either colored or white, which presents a markedly different appearance when the lamp is lighted from that presented when the lamp is out, and this difference is one equally as discernible in brightest sunlight as in blackest night.

The best form of apparatus embodying my invention at present known to me is illustrated in the accompanying sheet of drawings, in which—

Figure 1 is a side elevation of the lamp-hood or lantern. Fig. 2 is a vertical central section showing the lamps and interior parts of the lantern. Fig. 3 is a detail view showing the cylinder which forms the basis of the lamp-hood or lantern, and Fig. 4 is a further detail showing the slots in the caps.

1 is a cylinder forming the basis of the lamp structure or lantern. It is supported by a stem 2. Caps 3 and 4, containing thin translucent plates of glass or other suitable material 5 and 6, slip over the opposite ends of the cylinder 1 and with it form the lamp-hood. In the cylinder 1 are mounted back to back the reflectors 7 and 8, which are preferably corrugated, as shown, though a true parabola or other curve might be employed. In the foci of these reflectors are mounted electric incandescent lamps 9 and 10, which are preferably connected in series in a circuit whose terminals are shown at 11 and 12. The stem 2 has a flange or skirt 13, which may be mounted thereon by means of the internally-threaded hub 14. The inner ends of the caps 3 and 4 have slots 3^a and 4^a, (see Fig. 4,) which permit them to pass by the stem 2 and one overlap the other. The skirt or flange 13 extends beyond and overhangs these slots, thereby preventing the rain from entering them. The bead 18 on the cap 4 limits the extent of such overlapping. The two caps may be held in position by the pivoted hook 16 on one cap, as 4, and the stud 17 on the other cap, as 3, with which it engages.

The hand-hole 15 in cylinder 1 (see Fig. 3) affords access to the lamps and their connecting-wires. The caps 3 and 4 have portions 19 and 20, Fig. 2, which project beyond the glass plates.

In operation the lamps 9 and 10 are rendered incandescent by the passage of an electric current when certain signals are to be made. At night the difference between a lighted and an unlighted lamp is of course discernible at a glance, as is also the color of the signal-light. In the day-time a similarly-marked difference of appearance is also produced with my apparatus, for the following reasons: When a lamp is dead, the glass plates 5 and 6 present a dark dull appearance. When a lamp is lighted, however, it shows through the thin translucent glass plate and produces a marked change in its appearance. If the reflectors 7 and 8 are used, the effect is still more marked. The plates 5 and 6 change from a dark red or other color to a very light shade of the same color.

Through the plates can be seen the filament of the lamp marked out in a still more brilliant color, and the corrugations of the reflectors show in concentric rings of colored light. The effect is more noticeable at a distance from the lamp, if the same be properly focused, than it is from a nearer point of observation. The projecting portions 19 and 20 of the hood serve to shade the glass plate in part from the direct rays of the sun and heighten these differences of appearance above described.

Broadly speaking, the difference between the operation of the ordinary signal-lantern and mine, so far as at present understood, is that the ordinary lantern throws rays of colored light by means of lenses, which rays are completely lost in strong sunlight. My apparatus, on the other hand, does not, primarily, throw rays of external light, but produces a brilliantly-lighted interior which is visible through a colored window, (one of the translucent glass plates 5 or 6.) When said interior is not illuminated, it presents a dark background to the window, and the same is of dark color. When it is illuminated, it takes on a light color, because it is viewed through a slightly-colored pane of glass. Furthermore, signal-lanterns heretofore used have as a rule been designed to give a steady light, as in case of a ship's light, while my invention relates to variable signals, which convey different kinds of information, according to whether they are lighted or extinguished.

The main advantage of my invention is the saving of the cost of installation and of maintenance and operation of the ordinary mechanical signal or semaphore. A lamp is cheaper and more easily and quickly operated. As my invention is effective throughout the twenty-four hours of the day, it can entirely take the place of all other signals.

It is evident that various changes could be made in the details of the construction illustrated without departing from the spirit and scope of my invention so long as it embodied the essential feature of my discovery. Other forms of lamp might be employed. Other forms of reflectors might be employed, and in some cases reflectors might be omitted. Different forms of lamp-hood or lantern might be substituted so long as the thin translucent plates 5 and 6 were retained, and while

I have described these plates as of glass it is possible that other translucent material might be substituted for glass and the principle of my invention still be retained.

Having therefore described my invention, what I claim as new, and desire to protect by Letters Patent, is—

1. The combination of a cylinder, a supporting-stem therefor, two concave reflectors mounted therein back to back, a lamp in the focus of each reflector, caps fitting over either end of the cylinder provided with glass plates and slots engaging the stem, and a flange on said stem which overhangs said slots.

2. The combination of a cylinder, a supporting-stem therefor, two concave reflectors mounted therein back to back, a lamp in the focus of each reflector, caps fitting over either end of the cylinder provided with glass plates and slots engaging the stem, and a flange on said stem which overhangs said slots, said cylinder being provided with a side opening affording access to the lamps.

3. The combination of a cylinder, a supporting-stem therefor, two concave reflectors mounted therein back to back, a lamp in the focus of each reflector, caps fitting over either end of the cylinder provided with glass plates and slots engaging the stem, and a flange on said stem which overhangs said slots, the caps projecting beyond the glass plates.

4. The combination of a cylinder, a supporting-stem therefor, a concave reflector mounted in said cylinder, an electric lamp mounted in the focus of the reflector, a cap fitting over the end of the cylinder in front of the lamp and reflector provided with a glass plate opposite the end of the cylinder and a slot which engages the stem, and a flange on said stem which overhangs said slot.

5. A variable electric signal for day and night use comprising the combination of a hood, a plate of thin, translucent slightly-colored material mounted in said hood, an incandescent electric lamp behind said plate, and a concentrically-corrugated reflector behind the lamp, substantially as described.

Signed at Lansford, Pennsylvania, this 15th day of September, 1902.

HOWELL W. SOUDER.
